UNITED STATES PATENT OFFICE.

WILLIAM MUNSON, OF HYDE PARK, PENNSYLVANIA.

THILL-COUPING.

SPECIFICATION forming part of Letters Patent No. 228,832, dated June 15, 1880.

Application filed January 2, 1880.

To all whom it may concern:

Be it known that I, WILLIAM MUNSON, of Hyde Park, city of Scranton, in the county of Lackawanna and State of Pennsylvania, have 5 invented certain new and useful Improvements in Thill or Shaft Couplings for Vehicles; and I do hereby declare that the following is a full, clear, and exact description of the invention, which will enable others skilled 10 in the art to which it appertains to make and use the same, reference being had to the accompanying drawings, and to letters of reference marked thereon, which form a part of this specification.

15 My invention consists in a special construction of the draw-iron and of the shaft-iron, and in the manner and means whereby the latter is applied to and held to place by the draw-iron, and in a rubber plug having a 20 special form adapted to these parts and inserted in a special and novel manner.

Figure 1 is a view of the shaft-iron; Fig. 2, of the draw-iron; Fig. 3, of the rubber, and Fig. 4 of these parts put together for use.

25 The draw-iron A is shown without its clip or means for fastening it to the axle, which may be of any well-known kind.

b is a central longitudinal cut or opening, and c a concentric or arched transverse cut or 30 opening at the forward end of the draw-iron, this curve being described about a center or concentric bearing, d, and the result of such cuts is to afford two long and backwardly-turned hooks, e e, which reach back and extend over the centers d.

35 The rear wall, f, slants slightly forward from its top to bottom.

The shaft-iron G is provided with two curved or arched side pieces or knuckles, h h', 40 (one at each side,) projecting from its shank i, and also with a stop or extension, j, on its top, the knuckles h h' being adapted in size and in curvature to be received within the curved slots or openings c c, and to be moved 45 therein around the centers d, which are partial cylinders.

K is an india-rubber piece or plug of peculiar shape, as shown, and adapted, when the thill-iron is in place and down to its lowest 50 position, to be inserted in that rear part of the slot or opening b not occupied by the

thill-iron. This rubber K is made with a head, k', which prevents any possibility of its dropping through opening b, and it has a swell, l, on its front face to coincide with the centers or 55 cylinders d and with the concave part m of the shaft-iron G.

To put the parts together the piece G must be placed nearly in a vertical position, in order to permit its wings or knuckles h h' to 60 enter the mouths of the curved slots c, after which it is turned down as far as it will go—that is, until the knuckles reach the lowest parts of these slots. Next the elastic block or 65 plug K is inserted, by its smaller or headless end, into the opening provided for it, as above stated, and pressed down to place by the thumb or fingers until its head brings it to a halt. The device is now ready for use; and the rubber not only locks the shaft-iron so that it 70 cannot become accidentally dislodged, but it also acts as a spring and as a deadener of sound and a preventive of rattling, at the same time permitting all requisite vertical movement of the shafts, the top extension or 75 stop j in such case pressing against the head of the rubber plug with a good leverage.

The construction, it will be observed, is very simple, strong, and efficient. There are no rivets or bolts to be lost and no bolt-holes to 80 weaken the irons—no journals, latches, screws, hinges, nuts, or clasps to render it complex and to get out of order—while the two parts A and G, even unaided by the rubber, are so interlocked as to be almost incapable of separation, under ordinary conditions, while the 85 vehicle is in use.

I claim—

1. In combination, the draw-iron A, as made with the opening b, concentric slots c, and 90 concentric bearing d, and the shaft-iron G, as made with the lateral arched projections or knuckles h h', substantially as shown and described.

2. In combination with the draw-iron A and 95 shaft-iron G, having the stop j, the elastic plug K, formed with a head and with a swell, l, and adapted to be inserted to place, as set forth.

WILLIAM MUNSON.
